(57) CLAIM

I claim, the ornamental design of a broken light bulb remover, as shown and described.

DESCRIPTION

FIG. 1 is a frontal view of the broken light bulb remover of my design;

FIG. 2 is a back view of the invention of FIG. 1;

FIG. 3 is a side view of the edge of the invention of FIG. 1;

FIG. 4 is a side view of the opposite edge of the invention of FIG. 1, both side views being a mirror image;

FIG. 5 is a perspective view of the top edge of the invention of FIG. 1; and,

FIG. 6 is a perspective view of the bottom edge of the invention of FIG. 1.
